UNITED STATES PATENT OFFICE.

FRANK X. BACHLE AND JOHN C. L. KREBS, OF CLYDE, OHIO.

MULTIPLE-CYLINDER ENGINE.

No. 880,958.

Specification of Letters Patent.

Patented March 3, 1908.

Application filed June 13, 1907. Serial No. 378,691.

To all whom it may concern:

Be it known that we, FRANK X. BACHLE and JOHN C. L. KREBS, citizens of the United States, and residents of Clyde, in the county of Sandusky and State of Ohio, have invented a certain new and useful Multiple-Cylinder Engine; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to explosive engines, and particularly to rotary valves, for use in conjunction with engines employing three or more cylinders, and for the purpose of illustration the same is herein shown and described as being used in connection with a two-cycle four cylinder engine, but is not restricted to such use.

The employment of two-cycle engines for heavy work so far as we are aware has heretofore been impracticable on account of the low efficiency thereof due to the comparatively small charge that is admitted to the combustion end of the cylinder during the brief period that the inlet port is uncovered by the piston at the limit of its outgoing stroke.

The object of our invention is to overcome the above objections and to increase the practicability and efficiency of two-cycle engines of the two or more cylinder type by the provision in combination therewith of simple means whereby, in the case of a two cylinder engine, the charge is pumped into the combustion end of each cylinder by the piston of the other cylinder, and in the case of a three or more cylinder engine the charge is pumped into the combustion end of each cylinder by the pistons of two or more cylinders of the series thus in the latter case charging a cylinder with at least twice as much gas as is possible where each cylinder is only supplied with the charge created alone by its own piston, thus making the strength of the outgoing stroke of each piston approximately as efficient as the power-stroke of a four-cycle engine.

The operation, construction and arrangement of the parts of the invention are fully

described in the following specification and illustrated in the accompanying drawings, in which,

Figure 1 is a vertical section of the engine embodying our invention taken on the dotted line 1—1 in Fig. 5. Fig. 1^a is a partial section along the same line showing the position of the valve when the crank is at 60° past upper center on the down stroke. Figs. 2, 3 and 4 are diagrammatical vertical sections taken, respectively, on the dotted lines 2—2, 3—3 and 4—4 in Fig. 5. Fig. 5 is a side elevation of the engine with the rotary valve and its casing in longitudinal section on the dotted line 5—5 in Fig. 7. Fig. 6 is an inner side view of the rotary valve when in the position shown in Fig. 5, and Fig. 7 is a left hand end elevation of the engine.

Referring to the drawings, 1, 2, 3 and 4 designate in order from left to right the several cylinders of a two-cycle four-cylinder engine, each of which is provided with the usual receiving and distributing port 5 leading to the pumping-chamber 6 of its cylinder, the inlet or charging port 7 leading to the combustion end of its cylinder, and the exhaust-port 8. The pistons 9 are provided at their lower ends with the enlargements 9', which operate in the lower enlarged ends of the cylinders and are connected by their piston-rods 10 to a crank-shaft 11, the cranks of which are arranged in the usual manner, namely with the cranks of cylinders 1 and 2 on opposite sides of the shaft and at right angles to the cranks of cylinders 2 and 3, which latter are opposite to each other.

Secured to one side of and connecting the several cylinders of the engine, as shown, is the housing or valve-casing 12, which is formed with a longitudinal cylindrical chamber for receiving the rotary-valve 13, and for each cylinder is provided with the ports 14 and 15, which register, respectively, with the ports 5 and 7 of the cylinder.

The valve 13 is formed throughout its length with a central cylindrical chamber or passageway 16, and the surrounding chamber 17, the former of which will hereinafter be referred to as the "supply-chamber" and the latter as the "distributing-chamber." Both ends of the distributing-chamber and one end of the supply-chamber are closed, while the other end of the supply-chamber communicates with the carburetor. Pro-

- jecting from the closed end of the valve 13 through a box 18 secured to the casing 12 is a stub-shaft 19, which carries a gear-wheel 20. This gear meshes with an idler 21, which is 5 driven by a gear-wheel 22 on an end of the crank-shaft 11, said gears and idler being of equal size so that a single revolution is imparted to the valve at each revolution of the crank-shaft.
10. A group of ports 23, 24 and 25 is provided in the valve 13 for each cylinder, the ports 23 and 24 of each group being arranged in circular series to successively register with the associated port 14 in the casing 12 while the 15 port 25 is offset from the ports 23 and 24 in position to register with the associated port 15 in the casing. The ports 23, which may be termed the receiving ports, open communication with the supply-chamber 16 of 20 the valve and are so arranged that each registers with its port 5—14 on the down or outgoing stroke of the associated piston; the ports 24 open communication with the distributing-chamber 17 of the valve and are so arranged that each 25 registers with its port 5—14 on the up or compression stroke of the associated piston; and the ports 25 open communication with the distributing-chamber 17 of the valve and are so arranged that each 30 registers with its charging port 7—15 during the period that the same is uncovered by its piston, which is approximately during a quarter turn of the crank-shaft. It is thus apparent that inasmuch as the several cranks 35 of the crank-shaft are differentially positioned, the like ports of the several groups will also be differentially positioned or arranged in staggered relation around the valve.
40. The operation of our invention is as follows:—The supply-chamber 16 of the valve being in communication with the carburetor, the charges will be drawn from said chamber and into the pumping-chambers 6 of the 45 cylinders through the valve ports 23 and associated cylinder ports 5—14 on the down-strokes of the pistons, and on the up-strokes of the pistons these charges will be forced through the cylinder ports 5—14 and valve- 50 ports 24, which latter have moved in register with the ports 5—14 for such purpose, into the distributing-chamber 17 of the valve from which they are distributed to the proper cylinders above the pistons through 55 the valve ports 25 and cylinder ports 7—15. With a four cylinder engine two of the pistons are drawing in charges and distributing them to a different but common cylinder, as for instance, No. 1 cylinder has its charge 60 compressed therein by Nos. 2 and 4 pistons; No. 2 cylinder by Nos. 1 and 3 pistons; No. 3 cylinder by Nos. 1 and 4 pistons; and No. 4 cylinder by Nos. 2 and 3 pistons, thus causing the combustion end of each cylinder to 65 be charged with approximately twice as

much gas as would be the case were only one piston operating to charge it, as has heretofore been the case. Referring to Figs. 1, 1^a, 2, 3 and 4, it will be noted that when the crank-shaft is in the position shown, No. 2 piston will have nearly reached its limit of downward movement at which point the receiving port 23 is just about to close while the port 23 of No. 4 cylinder is just opening to the receiving port 5—14 of its cylinder. 70 During the movement of No. 2 crank approximately between the points *a* *b* in its revolution the charging port 7—15 of No. 2 cylinder will be uncovered by the piston and the associated valve port 25 will be in register therewith so that a charge that is being forced into the distributing-chamber 17 of the valve by Nos. 1 and 3 pistons will be caused to flow into No. 2 cylinder, which is 75 the only one open to the distributing-chamber during such period. As soon as the port 25 for No. 2 cylinder has passed its cylinder port 7—15, the valve port 25 to No. 4 cylinder comes in register with its port 7—15, which is just being uncovered by its piston 80 and a charge forced into said cylinder by Nos. 2 and 3 pistons, and the cylinders Nos. 1 and 3 are each then charged in the same manner in the order given, so that at each 85 quarter of a revolution of the valve one of the ports 25 is open to its cylinder and a charge is being compressed therein by the action of the pistons of two of the other cylinders.

It is apparent that by the use of our invention the speed of the engine may be regulated through the medium of the valve, as the speed may be increased by regulating the valve to cause the ports to open early to admit a full charge of gas, or the speed may 105 be decreased by regulating the valve to cause the ports to open late to admit only a part of a charge.

It is also apparent that should our invention be employed in connection with a three cylinder engine the valve ports will be arranged so that a different one of each of the like ports of the valve will register with their respective cylinder ports at approximately each third of a revolution of the valve. 110

Having thus described our invention, what we claim as new and desire to secure by Letters Patent, is,—

1. A multiple cylinder engine having its cylinders provided with pumping and combustion-chambers, said chambers each having a port communicating therewith, a crank-shaft and a rotary valve geared to revolve with the engine crank-shaft and having a gas supply-chamber and a gas distributing-chamber, said supply-chamber having ports arranged to register at different points in a rotation of the valve with the ports leading to the pumping-chambers of the cylinders, and said distributing-chamber 120
2. A multiple cylinder engine having its cylinders provided with pumping and combustion-chambers, said chambers each having a port communicating therewith, a crank-shaft and a rotary valve geared to revolve with the engine crank-shaft and having a gas supply-chamber and a gas distributing-chamber, said supply-chamber having ports arranged to register at different points in a rotation of the valve with the ports leading to the pumping-chambers of the cylinders, and said distributing-chamber 125
3. A multiple cylinder engine having its cylinders provided with pumping and combustion-chambers, said chambers each having a port communicating therewith, a crank-shaft and a rotary valve geared to revolve with the engine crank-shaft and having a gas supply-chamber and a gas distributing-chamber, said supply-chamber having ports arranged to register at different points in a rotation of the valve with the ports leading to the pumping-chambers of the cylinders, and said distributing-chamber 130

having two series of ports, one series of which registers with the pumping-chamber ports at different points in a rotation of the valve while the other series registers with the combustion-chamber ports at different points in a rotation of the valve.

2. A multiple cylinder engine having its cylinders each provided with pumping and combustion-chambers which have ports communicating therewith, a rotary valve having a supply-chamber provided with ports arranged to register at different times with the pumping-chamber ports when the valve is rotated and having a distributing-chamber provided with a series of receiving and a series of discharging ports, the former of which ports register at different points with the pumping-chamber ports and the latter with the combustion-chamber ports when the valve is rotated, and means for rotating the valve at a predetermined speed.

3. A multiple cylinder engine having its cylinders provided with pumping and combustion-chambers having ports communicating therewith, a rotary valve having a supply-chamber and a distributing-chamber, the former of which is provided with a series of staggered ports for communicating with the pumping-chamber ports when the valve is rotated and the latter being provided with a series of staggered ports for communicating with the pumping-chamber ports and a series of staggered ports for communicating with the combustion-chamber ports when the valve is rotated, and means for rotating the valve at a predetermined speed.

4. A multiple cylinder engine having its cylinders provided with pumping and combustion-chambers, said chambers each having a port communicating therewith, a rotary valve forming a distributing-chamber and having a series of ports communicating with a source of gas supply and intended to register with the pumping-chamber ports as the valve rotates and a double series of ports communicating with the distributing-chamber, one series of which registers with the pumping-chamber ports and the other with the combustion-chamber ports when the valve is rotated, a source of gas supply, and means for rotating the valve.

5. A multiple cylinder engine having its cylinders provided with pumping and combustion-chambers each having a port communicating therewith, a rotary valve having a chamber in communication with a source of gas supply and provided with ports which register with the ports of the pumping-chambers of the cylinders at predetermined points in a revolution of the valve, and a distributing-chamber provided with ports which register with the ports of the pumping-chambers and ports which register with the ports of the combustion-chambers at

predetermined points in a revolution of the valve, a source of gas supply, and means for rotating the valve.

6. A multiple cylinder engine having its cylinders provided with pumping and combustion-chambers, each of which chambers is provided with a port, a casing secured to the cylinders and having ports registering with the ports in the pumping and combustion-chambers, a rotary valve mounted in the casing and having a plurality of gas supply ports arranged to register with the ports in the pumping-chambers at predetermined points in a revolution of the valve, said valve also having a distributing-chamber provided with a series of ports for registering with the ports in the pumping-chambers at predetermined points in a revolution of the valve, and a series of ports for registering with the ports in the combustion-chambers at predetermined points in a revolution of the valve, and means for rotating the valve at a predetermined speed.

7. A multiple cylinder engine having its cylinders provided with pumping and combustion-chambers, each having a port leading thereto, a rotary valve forming a supply-chamber and a distributing-chamber and having a group of three ports for each cylinder, one port for opening communication between the supply-chamber and the pumping-chamber port in its cylinder at a predetermined point in a revolution of the valve, and the other two opening from the distributing-chamber, and one intended to register with the pumping-chamber port and the other with the combustion-chamber port of the associated cylinder at predetermined points in a revolution of the valve, and means for rotating the valve, substantially as described.

8. A multiple cylinder engine having its cylinders provided with pumping and combustion-chambers, each having a port leading thereto, a piston in each cylinder, a source of gas supply, a rotary valve having a chamber in communication with the gas supply and from which the cylinders draw their charges through the ports in the pumping-chambers in the pumping-operations of the pistons, and having a chamber adapted to communicate at different times with the ports both in the pumping and combustion-chambers when the valve is rotated, whereby the compressing operations of the pistons cause a charge to be forced from a plurality of the pumping-chambers through the valve-chamber having the said two series of ports and into a combustion-chamber of one of the other cylinders of the set, and means for rotating the valve.

9. A multiple cylinder engine having its cylinders provided with pumping and combustion-chambers, each of which chambers is provided with a port, a piston in each cylinder

der, a source of gas supply, a rotary valve-member having a chamber in communication with the gas supply and provided with ports adapted to communicate at different times with the ports in the pumping-chambers during a revolution of said member, said member also having a chamber provided with ports arranged to open communication through the chamber between the combustion-chamber of one cylinder of the set and the pumping-chambers of a plurality of other cylinders of the set, whereby the pistons of a plurality of the cylinders operate to compress a charge in one of the cylinders of the set.

10. A multiple cylinder engine having its cylinders provided with pumping and combustion-chambers, each having a port communicating therewith, a piston in each cylinder, a source of gas supply, a rotary valve associated with the cylinders and having an inner gas supply-chamber communicating with the gas supply, and a surrounding distributing-chamber, the supply-chamber having ports adapted to communicate at different times in a revolution of the valve with the ports in the pumping-chambers, and the distributing-chamber having receiving ports arranged to communicate at different 25 times in a revolution of the valve with the ports in the pumping-chambers and having discharging ports adapted to communicate at different points in a revolution of the valve with the ports in the combustion-chambers,

the relative arrangement of said two sets of 35 ports in the distributing-chamber being such that the pistons of a plurality of cylinders will operate to compress a charge through said distributing-chamber into the combustion-chamber of one of the other cylinders, 40 and means to rotate the valve.

11. A multiple cylinder engine having its cylinders provided with pumping and combustion-chambers, each having a port in communication therewith, the pumping-chambers having communication with a source of gas supply from which they draw their charges during the pumping operations of their pistons, a source of gas supply, a piston in each cylinder, and a rotary member having a chamber provided with ports arranged to open communication through the chamber between the combustion-chamber of one cylinder of the set and the pumping-chambers of a plurality of other cylinders of the 55 set when the member is rotated, whereby the pistons of a plurality of the cylinders operate to compress a charge in the combustion-chamber of one of the other cylinders of the set, substantially as described. 60
